UNITED STATES PATENT OFFICE.

BRYAN HERBERT SMITH, OF NEW YORK, N. Y., ASSIGNOR TO CLARENCE WHITMAN & CO., INC., OF NEW YORK, N. Y., A CORPORATION OF NEW YORK.

DESIGN FOR COTTON PONGEE SHIRTING.

46,372.

Specification for Design.

Patented Sept. 8, 1914.

Application filed July 3, 1914. Serial No. 848,951. Term of patent 3½ years.

To all whom it may concern:

Be it known that I, BRYAN HERBERT SMITH, a citizen of the United States, and a resident of the borough of Brooklyn, county of Kings, New York city, New York, have invented a new, original, and ornamental Design for Cotton Pongee Shirting, of which the following is a specification.

Reference is to be had to the accompanying drawing, which illustrates a sample of the fabric, showing the new design.

In the drawing *a* represents a colored stripe known as satin about half the width of the woven colored stripe *h*; *b* is a stripe

of plain weave; *c* a cord; *d* a plain weave; *e* a cord; *f* plain weave; *g* a cord; and *h* a woven colored stripe, the color of which is less pronounced than the color of the satin stripe *a*; *i* is a section of plain weave. Unless otherwise specified, the fabric sections, cords, etc., are light colored, or white.

I claim:

The ornamental design for cotton pongee shirtings, as shown and described.

BRYAN HERBERT SMITH.
